UNITED STATES PATENT OFFICE.

MONROE J. MECHLING, OF DUN GLEN, OHIO.

TROLLEY OR FEED WIRE ANCHOR FOR MINES.

Application filed May 2, 1923. Serial No. 636,276.

To all whom it may concern:

Be it known that I, MONROE J. MECHLING, citizen of the United States, residing at Dun Glen, in the county of Jefferson and 5 State of Ohio, have invented certain new and useful Improvements in Trolley or Feed Wire Anchors for Mines, of which the following is a specification.

This invention relates to an improved 10 trolley or feed wire anchor for mines and seeks, among other objects, to provide a simple and efficient device which may be readily embedded in the roof of a mine for anchoring the end of a trolley wire or the 15 like.

The invention seeks, as a further object, to provide a device which will be constructed to effectually withstand the pulling strain of the trolley wire.

20 And the invention seeks, as a still further object, to provide a device which, when embedded in the roof of a mine, will be prevented from dropping down.

Other and incidental objects will appear 25 hereinafter.

In the drawings:

Figure 1 is a side elevation showing my improved anchor in use,

Figure 2 is a front elevation of the 30 device, and

Figure 3 is a fragmentary side elevation showing a slight modification of the invention.

In carrying the invention into effect, I 35 employ a preferably cylindrical shank 10 tapered toward its upper end and upset to define a preferably flat forwardly overhanging spur 11. Near its lower end, the shank is provided with an annular stop shoulder 40 12 and, as will be observed, the spur 11 lies within the diameter of the shank at the upper face of said shoulder. Formed on the shank at its lower extremity is a rearwardly directed head in the nature of a hook 13

45 provided with a slot or opening 14 entering through the front face of the head. Formed on the head in spaced relation to the shank is an upwardly and rearwardly divergent bracing leg 15 lying in a plane with the 50 shank and provided with a flat end face in a plane with the upper face of the shoulder 12.

In use, a vertical bore is formed in the roof of the mine to accommodate the shank

10 when, as suggested in Figure 1 of the 55 drawings, the shank is inserted into said bore until the stop shoulder 12 strikes the roof, the head or hook 13 being, of course, faced way from the direction of pull of the trolley wire or feed wire to be anchored. 60 When the shoulder 12 is thus seated against the roof of the mine, the leg 15 will, as will be seen, be caused to coincidentally engage the mine roof in the rear of the shank for bracing and supporting the shank while the spur 11 at the upper end of the shank will sink into the wall of the bore in the mine roof for securing the device in place. Thus, a trolley wire or feed wire may be engaged 65 with the head or hook 13 to be anchored by 70 the device and, if desired, a turn buckle, as conventionally illustrated in dotted lines at 16, may be employed for connecting the trolley wire or feed wire with the device, so that said turn buckle may be adjusted for 75 tensioning the wire. As will be perceived, the leg 15 of the device will rigidly brace the shank 10 against the rearward strain of the wire so that the device will thus provide 80 a secure and firm anchor for the wire.

In Figure 3 of the drawings, I have illustrated a slight modification of the invention which is practically identical with the preferred embodiment with the exception that the shank of the device, indicated at 10', 85 is formed at its lower end with a rearwardly directed head in the nature of an eye 17, said head or eye carrying a rearwardly directed leg 18 corresponding to the leg 15 and being provided with a central opening 19.

Having thus described the invention, what is claimed as new is:

An overhead anchor for mine trolley wires consisting of a shank to be inserted in a bore in the roof of the mine and having a stop shoulder intermediate its ends to abut the roof, the shank above said shoulder defining a longitudinal spur adapted to embed itself in the wall of the bore, a head at the lower end of the shank having an opening therethrough to be engaged by the trolley wire terminal, and a bracing leg rising from the head in divergent relation to the shank and abutting the roof in the 105 plane of the stop shoulder.

In testimony whereof I affix my signature.

MONROE J. MECHLING. [L. s.]
